HEINRICH BANGERT AND GUSTAV HÜHN, OF DUSSELDORF, GERMANY.

REGENERATIVE FURNACE.

Application filed December 30, 1927, Serial No. 243,589, and in Germany January 20, 1923.

Our invention relates to improvements in regenerative furnaces. Burners for regenerative furnaces such as are now in use are subject to rapid wear because the direction of the flame is changed when changing over from one regenerator to the other one, so that the parts of the burner, and more particularly the mouth thereof are exposed to changing temperatures, which causes rapid destruction of the brick work. The object of the improvements is to provide a burner in which the wear is reduced, and with this object in view our invention consists in constructing the burner so that the direction of the flame is not changed when changing from one regenerator to the other one, and in which therefore the mouth of the burner is always exposed to the same temperature. In carrying out the invention we provide the burner with two passages for alternately supplying the gas and conducting the heat to the regenerator chambers, and an air intake passage, the said passages being so disposed relatively to one another that only the gates controlling the regenerator chambers must be set for supplying the gas to the burner from one chamber or the other.

For the purpose of explaining the invention several examples embodying the same have been shown in the accompanying drawings in which the same reference characters have been used in all the views to indicate corresponding parts. In said drawings,

Fig. 1, is a sectional elevation of the furnace taken on the line 1—1 of Fig. 2,

Figs. 2 and 3, are sectional plan views taken on the line 2—2 of Fig. 1 and showing the burner connected respectively with one or the other of the regenerator chambers,

Fig. 4, is a sectional plan view taken on the line 4—4 of Fig. 1 and showing the passage for supplying the air,

Fig. 5, is a sectional plan view similar to the one illustrated in Figs. 2 and 3 and showing a burner provided with a single mouth,

Fig. 6, is a sectional elevation taken on the line 6—6 of Fig. 7 and illustrating a modification of the burner, and

Fig. 7, is a top plan view of Fig. 6.

In the example shown in Figs. 1 to 4, the furnace comprises a heating chamber 7 and a regenerator 8 comprising two chambers

adapted to communicate through passages 9 either with the supply of gas or with a stack, the said chambers being connected with the furnace through vertical passages 10 and 11 formed at their top ends with horizontal passages 17, 18. In the example shown in the figures there are three passages 10 and two passages 11. Further, the furnace comprises a transverse passage 12 connected with a blower for supplying air and communicating with the furnace through passages 13. At the intake end the furnace is divided by vertical partitions 14 into four passages 15. The passages 17, 18, 13 and 15 provide the multiple burner of the furnace. As appears from Figs. 1 and 2, the said passages meet at points indicated in Figs. 2 and 4 by the reference character 16, and the passages 17, 18 and 15 are disposed at angles of about 120°, the said angles having been indicated in Fig. 2 by the reference character ω .

In Figs. 2 and 3 we have indicated the flow of the gases through the burner. As shown in Fig. 2, the regenerator chamber connected with the passages 11 is connected with the supply of gas, the said gas being heated within the regenerator chamber and flowing upwardly through the passages 11. At the top end of the said passages the currents of gas are divided each into two branches one flowing to the right and the other to the left through the passages 17 and 18, and each branch current is again divided into two branches, the main portion flowing through one of the passages 15, and the other part flowing through a passage 18 and to one of the passages 10. At the point 16 air for supporting combustion is admixed to the gas, which air flows downwardly through the passages 13. The products of combustion flowing through the passages 15 are used for heating the furnace, and the products of combustion flowing downwardly through the passages 10 are used for heating the second regenerator.

After the said second regenerator has been heated, and the first-named regenerator through which so far the gas has been supplied to the furnace has cooled off, the regenerators are reversed, whereupon the gas flows upwardly through the passages 10, and portions of the products of combustion flow downwardly through the passages 11. It

will be understood that in both cases the flow of the products of combustion through the passages 15 of the burner is the same, and that therefore the mouth of the burner is always kept at the same temperature.

In Figs. 1 to 4 we have shown a multiple burner, that is a burner provided with a plurality of passages 15 and cooperating passages 10 and 11. But we wish it to be understood that our invention is not limited to this feature. Thus, Fig. 5 shows a burner having a single passage 15 connected with two vertical passages 10 and 11 adapted to be alternately connected to both regenerators. Otherwise the construction of the furnace is the same as has been described with reference to Figs. 1 to 4, and the same letters of reference have been used to indicate corresponding parts.

In the example so far described the passages 15, 17 and 18 are disposed in a horizontal plane. In Figs. 6 and 7 we have shown a modification in which the said passages are disposed in a vertical plane. As shown in the said figures, the furnace 20 is provided with two regenerator chambers 21 and 22 communicating through vertical passages 23 and 24 with the burner of the furnace. As shown, the said burner comprises a chamber 26 communicating with the furnace 20 through passages 27. The passages 23 open into the said chamber at the bottom thereof, and the passages 24 are formed at their top ends with laterally directed portions 28 opening into the chamber at the rear thereof. Above the chamber 26 there is a transverse passage 29 communicating through vertical passages 30 with a supply of air.

As shown in Fig. 6, the gas flows upwardly from the regenerator chamber 21 through the passage 23, and it is mixed with air within the chamber 26. The main part of the products of combustion flows to the left and through the passages 27, while the remaining part flows downwardly through the passage 24 and the regenerator chamber 22. After reversing the regenerator chambers, the gas flows upwardly through the passage 24, and, after being mixed with air, it is divided into two branch currents one flowing downwardly through the passage 23 and the regenerator chamber 21 and the other one flowing through the passages 27.

Also in this case the products of combustion flow through the passages 27 of the burner in the same direction whether the gas is supplied from regenerator chamber 21 or 22.

The passages 15, 17 and 18 or 23, 28 and 27 may be disposed at different angular positions, provided that the passages are disposed so that the current of gas can be divided into branch currents one flowing through the furnace and the other to one of the regenerator chambers, and that the air is thoroughly admixed to the gas. The amount of gas flowing

to the regenerator chamber to be heated is smaller than the amount of gas flowing through the furnace. Therefore the angle included between the passages 17 and 18 may be smaller than 120°. In the examples illustrated in the figures the air is supplied from the top of the burner. But we do not limit ourselves to this feature, and in some cases the air is supplied from below or between the passages 17 and 18.

We claim:

1. A regenerative furnace having two passages for alternate communication with a source of gas supply and with a stack and connected with separate regenerator chambers, a burner passage communicating with the furnace, and a passage for supplying air, all the said passages meeting at a common air and gas mixing and mixture ignition point and the three first-named passages being so relatively arranged as to effect a division of the products of combustion into two portions supplied respectively to the burner passage and that passage of the first-named passages which at the time being communicates with the stack.

2. A regenerative furnace having two passages for alternate communication with a source of gas supply and with a stack and connected with separate regenerator chambers, a burner passage communicating with the furnace, and a passage for supplying air, all the said passages meeting within the burner at a common air and gas mixing and ignition point, the said passages communicating with the regenerator chambers and the furnaces being disposed substantially at angles of 120° so as to cause division of the products of combustion into streams respectively supplied to the burner passage and to the one of the pair of passages which at the time being communicates with the stack.

3. In a burner according to claim 1, the feature that the said air supplying passage and the passages communicating with the regenerator chambers open into a subdivided chamber forming a multiple furnace burner.

4. A regenerative furnace having two regenerator chambers, sets of passages alternating in arrangement with each other and communicating respectively with the respective regenerator chambers, said sets of passages being designed for connection alternately with a source of gas supply and a stack, a burner passage leading to the furnace, said passages intersecting at a common point, and baffles arranged to deflect portions of the products of combustion passing to the burner passage from the set of passages communicating with the source of gas supply toward the set of passages communicating with the stack.

5. In a regenerative furnace, a furnace chamber, two regenerator chambers, a set of passages connected with one regenerator

chamber, a set of passages connected with the
ther regenerator chamber, said sets of pas-
sages serving alternately as fuel supply pas-
sages for the furnace and heating flues for
5 the regenerators, a burner passage between
said sets of passages and the furnace cham-
ber, said burner passage being subdivided
into a plurality of passages staggered with
relation to the sets of regenerator chamber
10 passages and each communicating at an angle

with a passage leading to each regenerator
chamber, and means for conducting air for
mixture with the gas at the points of connec-
tion of the burner passages with the generator
chamber passages.
